UNITED STATES PATENT OFFICE.

JESSE A. B. SMITH, OF FAIRFIELD, CONNECTICUT, ASSIGNOR TO UNDERWOOD TYPEWRITER COMPANY, OF NEW YORK, N. Y., A CORPORATION OF DELAWARE.

INVOICE SHEET.

Application filed October 18, 1920. Serial No. 417,655.

To all whom it may concern:

Be it known that I, JESSE A. B. SMITH, a citizen of the United States, residing in Stamford, in the county of Fairfield and State of Connecticut, have invented certain new and useful Improvements in Invoice Sheets, of which the following is a specification.

This invention relates to entry sheets for use in a typewriting machine, such, for example, as a bill-head or statement-sheet upon which successive items are entered from time to time or from day to day for a suitable period, commonly until the end of a month, when the completed statement is sent to the customer. Such sheets have been commonly provided with a detachable lefthand marginal part or lateral filing margin for temporarily binding or filing the entry sheet between the times of the typing of the successive entries or items thereon. This filing margin is torn off before sending the bill or statement to the customer, in order thereby to give a neat and pleasing appearance to the bill by the removal of this unsightly part, which commonly is provided with a plurality of large holes for use in the temporary filing or binding of the entry sheet.

By reason of the repeated insertions of the entry sheet into the typewriting machine, the top or leading edge thereof and particularly the upper corners have a tendency to become worn and frayed, so that by the time the end of the month is reached, the bill or statement is not in a neat or presentable condition for sending to the customer. This poor or damaged condition of the sheet has been in large part caused by the tendency of the corners at the top or leading end of the sheet to catch upon parts of the typewriting machine.

An object of the invention is to produce an entry sheet or statement-sheet in which the part which is to be sent to the customer will not present fraying or other imperfection due to having been put through the typewriting machine many times, and furthermore in this connection to produce an entry sheet having a detachable filing margin, while leaving the entry-containing body part of the sheet in symmetrical shape for sending to the customer after the filing margin has been torn off.

According to the present invention, the entry sheet comprises a body part for re-

ceiving the successive items or entries, a detachable lateral marginal part at one side of the body part and providing for the temporary filing of the sheet between the times of making the successive entries, an upper extension projecting from the top of only the body part, to the exclusion of the detachable lateral filing marginal part, said extension carrying rounded corners, thus providing for or facilitating the passage of the entire width of the sheet (including said marginal part) through the typewriting machine repeatedly without tearing, fraying or noticeable evidence of wear, and also providing a main or body part of pleasing symmetrical appearance for sending to the customer, after the detachable lateral filing marginal part has been detached from the main or body part of the entry sheet.

Other features and advantages will hereinafter appear.

In the accompanying drawing, the figure shown is a plan or face view of a bill-sheet or statement-sheet embodying the invention.

The statement-sheet or bill-sheet, illustrated in the accompanying drawing, comprises a main body part A, which, in this particular sheet, is shown as made up of an item-receiving lower part 1 upon which the various items may be successively entered, and an upper detachable stub part 2 to contain the customer's address and to be returned by him with his check, as has heretofore been customary. The stub part 2 is shown as joined to the entry-carrying part 1 by means of a line of perforations 3 as common heretofore. The entry sheet is provided at the left side of the body part A thereof with a filing margin or lateral marginal part 4, having therethrough large holes 5, shown as two in number, for convenience in temporarily binding or filing the entry sheet by its marginal part 4, between the times of the making of the successive entries upon the lower part 1 of the body part A. The lateral marginal part or filing margin 4 is joined to the main body part A, comprising the lower part thereof 1 and the upper part thereof 2, by means of a vertical weakened line of detachment, indicated in the drawing as a line of perforations 6, whereby the lateral filing margin 4 may be accurately and easily detached from the main body part A before sending the latter to the customer.

According to the present invention, the upper end of the body part A of the statement, which also in the particular form shown is the top or upper end of the detachable stub 2, is provided with an upper extension 7 projecting above the adjacent upper end of the filing margin 4, as shown at the left in the drawing, and as indicated at the right by the detached indicating line 8. This 10 upwardly projecting extension 7 forms the upper end or leading edge of the main body part A, which is eventually sent to the customer. The top extension 7 is added for the purpose of providing blunt or rounded 15 corners 9, which, by reason of their rounded shape, facilitate the repeated passage of the entire width of the sheet through the typewriting machine without perceptible wear or damage to the corners or leading edge of the 20 sheet provided by this extension 7. It is to be noted that the top extension 7 extends along the full width of the upper end of the entry-carrying body part A, but that it terminates at the vertical weakened line of 25 detachment 6, so that, while this upper extension projects above, it does not extend along the upper end of the lateral filing marginal part 4, whereby the rounded corners 9 are carried by the upper end of 30 the body part A, at the top of the detachable stub part 2, to the exclusion of the detachable lateral filing marginal part 4, the upper end of which terminates at a line along which the upper extension 7 is joined 35 to the top of the body part A, as is clearly shown in the drawing.

It will now be evident, by reason of the carrying out of the present invention as above described, that at the end of the month 40 and after the usual tearing off of the filing margin 4 along the vertical line of perforations 6, which removes and does away with this now unnecessary and more or less unsightly marginal part, the main body part 45 A of the bill or statement, together with its upper extension 7, will be of symmetrical outline with two lower square corners and two upper similarly rounded corners 9, thereby presenting a pleasing appearance. 50 Also it will be evident that this main body part A when sent to the customer will still be in good condition without appreciable wear or other evidence at the top or elsewhere of having been passed repeatedly 55 through the typewriting machine in making the various entries thereon.

Variations may be resorted to within the scope of the invention, and portions of the improvements may be used without others.

60 Having thus described my invention, I claim:

1. For use in a typewriting machine, an entry sheet comprising a body part, a lateral filing marginal part at one side of the body 65 part and detachably connected therewith

along a vertical weakened line of detachment, and an upper extension projecting from and extending along the full width of the upper end of the body part and terminating at said vertical weakened line of detachment to form a leading edge for the body part and having blunt right and left upper corners to be carried by and remain upon the upper end of the body part after the detachment therefrom of the lateral filing marginal part. 70 75

2. For use in a typewriting machine, an entry sheet comprising a body part for having successive entries typed thereon, a lateral filing marginal part at one side of the body part and detachably connected therewith along a vertical weakened line of detachment providing for easy detachment of the filing marginal part from the body part when the entries on the body part are complete, and an upper extension projecting from and extending along the full width of the upper end of the body part to form a leading edge therefor and having both of its corners rounded, said upper extension 80 terminating at said vertical weakened line of detachment, so that both of said rounded corners will be carried by the upper end of the body part, whereby said rounded corners will facilitate the repeated insertion of 85 the entry sheet in the typewriting machine, and will thereby prevent the leading end of the body part from becoming appreciably worn or frayed by reason of such repeated insertion, and also whereby the upper end 90 of the body part will be left in symmetrical shape with similar rounded right and left upper corners after the detachment therefrom of said lateral filing marginal part. 95 100

3. For use in a typewriting machine, an entry-sheet comprising a body part for having successive entries typed thereon, a lateral filing marginal part at one side of the body part and detachably connected therewith along a vertical weakened line formed by a 105 series of perforations providing for easy detachment of the filing marginal part from the body part when the entries on the body part are complete, said filing marginal part having holes therethrough for the purpose 110 of filing the entry-sheet between the times of the making of the successive entries on the body part thereof, and an upper extension projecting from and extending along the full width of the upper end of the body part and terminating at said vertical weakened line of detachment to form a leading edge for the body part and having rounded right and left upper corners to be carried by and remain upon the upper end of the 115 body part after the detachment therefrom of the lateral filing marginal part. 120 125

4. For use in a typewriting machine, an entry-sheet comprising a body part for having successive entries typed thereon, a lateral 130

5 filing marginal part at the left side of the body part and detachably connected therewith along a vertical weakened line of detachment providing for easy detachment of
10 the filing marginal part from the body part when the entries in the body part are complete, the filing marginal part having holes therethrough for the purpose of filing the entry-sheet between the times of the making of the successive entries on the body part thereof,
15 10 of the successive entries on the body part thereof, and an upper extension projecting from and extending along the full width of the upper end of the body part and terminating at said vertical weakened line of detachment to form a leading edge for the body part and having rounded right and left upper corners to be carried by and remain upon the upper end of the body part after the detachment therefrom of the lateral filing marginal part.
20 25 5. For use in a typewriting machine, an entry-sheet comprising a body part for having successive entries typed thereon, a lateral filing marginal part at the left side of the body part and detachably connected therewith along a vertical weakened line of detachment providing for easy detachment of

the filing marginal part from the body part when entries in the body part are complete, the filing marginal part having holes therethrough for the purpose of filing the entry-sheet between the times of the making of the successive entries on the body part thereof, and an upper extension projecting from and extending along the full width of the upper 30 end of the body part and terminating at said vertical weakened line of detachment to form a leading edge for the body part and having rounded right and left upper corners to be carried by and remain upon the 35 upper end of the body part after the detachment therefrom of the lateral filing marginal part, the lateral filing marginal part terminating at its upper end at a line on which the upper extension is joined to the 40 top of the body part, so that the upper end of the lateral marginal filing part will be below the upper edge of the upper extension of the body part to the extent of the width of the upper extension.
